TABULATOR MECHANISM FOR TYPEWRITING-MACHINES.

1,347,757.

Specification of Letters Patent. Patented July 27, 1920.

Application filed July 8, 1919. Serial No. 309,460.

To all whom it may concern:

Be it known that we, ERIC JULIUS PILBLAD and ARTHUR TOMLINSON, subjects of the King of England, both residing at London street, North Evington, Leicester, in the county of Leicester, England, have invented certain new and useful Improvements in Tabulator Mechanisms for Typewriting-Machines, of which the following is a specification.

This invention is for improvements in or relating to tabulator mechanisms for typewriting machines, such mechanism generally comprising a tabulator key-lever having operative connections between it and (1) the carriage-escapement and (2) a tabulator-stop, such that when the tabulator-key is operated the carriage-escapement is released and the tabulator-stop is brought into the path of an abutment on the carriage. This operation releases the carriage which then moves—under the action of its controlling-spring—until its projection engages the stop whereby it is brought to rest.

A primary object of this invention is to provide an improved construction of mechanism which, after the tabulator-key has been operated, shall arrest the same in the position into which it is brought to maintain the disengagement of the carriage-escapement until the movement of the carriage is arrested by the stop, whereby liability to damage the escapement is obviated and it is not necessary to hold the tabulator-key depressed after the movement of the carriage has commenced.

Another object is to provide that if the tabulator-key has been accidentally depressed after the carriage has passed the last tabulator-stop, then the tabulator-key can be released and the carriage-escapement can be reengaged by sliding the carriage along its guides against the action of its controlling spring.

To these and other ends, the invention consists in the construction, arrangement and combination of parts described hereinabove and pointed out in the claims.

The invention will be clearly understood from the following description, taken in connection with the accompanying drawings, which illustrate a preferred embodiment of the invention, and in which—

Figure 1 is a section taken in a direction transversely through the carriage and showing only those portions of the mechanism relevant to the present invention, in the position they assume before actuation of the tabulator-key;

Fig. 2 is a plan view of Fig. 1;

Fig. 3 is a similar figure to Fig. 1, showing the parts in the position they assume after operation of the tabulator key;

Fig. 4 is a plan view of Fig. 3, and

Fig. 5 is an elevation of a portion of the mechanism viewed from the right of the preceding figures, that is, from the back of the machine.

The slide of the carriage carrying the platen-roller and its component parts is shown at A, and an escapement-rack also supported on the carriage is shown at B. This rack B is swingingly supported on the carriage so that it may be moved to the position shown in Fig. 3 in relation to spring-controlled and fixed dogs C and C¹ respectively, operated in a known manner from the universal rail. For the sake of clearness, the connections between the carriage and the rack B are not shown, nor are the guides for the slide A illustrated, although their provision in the machine will be understood. Supported at the back of the machine is a tabulator-rail D, whose two ends are supported in arms D¹ secured to a rock-shaft D² carried in any convenient manner in the frame of the machine.

The rock-shaft D², (and with it the rail D), is movable endwise in bearings D³ against the action of a coiled spring D⁴, which normally holds the rail to the left in the position shown in Fig. 5. Secured to the rock shaft so as to move with it is a clip E having a downwardly extending portion E¹ engaging the back end F¹ of a tabulator key-lever F. The back end F¹ is shown as an extension of F secured thereto by

means of the screws F^2 . The lever F is shown as slotted at F^3 to receive a bolt F^4 screwing into a fixed portion G of the machine. The slot F^3 and bolt F^4 limit the movement of the key-lever F . Pivoted at H^1 to the part G of the machine is a catch H , having a hook or lip H^2 at one end and a cranked extension H^3 at its other end. The lip H^2 is adapted to engage with a slot F^5 formed in the edge of the key-lever F , while the end H^3 is adapted to be engaged by an upwardly extending portion E^2 of the clip E .

Pivoted to the key-lever F at J^1 is an arm J having a part J^6 engaging with the catch H on that side of its pivot toward the lip H^2 . At the extremity of the lever J is mounted a pawl J^2 , more clearly shown in Fig. 5, controlled by a spring J^3 so as normally to hold a stop J^4 of the pawl J^2 in contact with the upper edge of the lever J . The pawl J^2 has an extension J^5 adapted to engage, in the manner hereinafter to be described, with teeth K^1 formed on the lower edge of a swinging-bar K . This bar extends throughout the length of the carriage and is supported at each end in arms K^2 pivoted to the carriage as at K^3 .

The lip H^2 of the lever H is held pressed toward the edge of the key-lever F by means of a spring H^4 ; and the key-lever F is controlled by a spring, not shown, tending to draw it toward the front of the machine, that is to the left of Figs. 1 to 4.

35 The operation of the parts is as follows:—

During the normal operation of the machine, when the tabulator-mechanism is not being used, the parts are in the position as shown in Fig. 1. When, however, it is desired to use the tabulating mechanism the tabulator key-lever is manually operated to move it in the direction of the arrow F^6 in Fig. 1. This movement brings the slot F^5 of the key-lever into the position in which it is engaged with the lip H^2 and is thus held in the position into which it has been manually operated. At the same time by means of its extensions F^1 , the rock-shaft D^2 is moved, bringing the parts into the position shown in Fig. 3, while the rack B is disengaged from the teeth of the dogs C by means of a pillar F^7 secured to and moving with the key-lever F . This latter operation releases the carriage-escapement and allows the carriage to slide freely under the action of its controlling-spring. The arrest of the carriage is brought about by a tabulator-stop D^5 adjustable as to its position along the rail D and adapted to be secured thereon in any desired position. It will be readily appreciated that the adjustment of the stop D^5 along the rail D regulates the position of the sliding movement of the

carriage in which the latter is to be arrested 65 for tabulating purposes. When the carriage engages the stop D^5 , as for example by means of a projection L , Fig. 5, the momentum of the carriage shifts the rail D and the rock-shaft D^2 endwise to the right 70 of Fig. 5 against the action of the spring D^4 . In so doing the projection E^2 of the clip E engages with the end H^3 of the catch H , thereby swinging it about its pivot H^1 , and withdrawing the lip H^2 from engagement with the slot F^5 . This disengagement 75 of the catch from the lever F permits the latter to return to its normal position under the influence of its controlling-spring, that is to say permits it to move in a direction 80 against that of the arrow F^6 , and in so doing the pillar F^7 is moved to allow the rack B to reengage with the dogs C , while the rock-shaft D^2 turns, with its component parts in the position shown in Fig. 1; thus 85 it will be seen that when the carriage is brought into engagement with the stop D^5 two operations occur.

(1) Owing to the rock-shaft D^2 only having a limited endwise movement the sliding 90 movement of the carriage is arrested and

(2) Substantially simultaneously with the stopping of the carriage the carriage-escapement is reengaged, and also the tabulator key-lever and its mechanism is reset 95 for the next tabulating operation.

When, however, several tabulator-stops are employed on the rail D and the carriage has moved past the last stop, for example, owing to the accidental depression 100 of the tabulator-key, the parts, which will still remain in the position shown in Fig. 3, may be reset by moving the carriage against the pull of its controlling-spring. This movement brings one of the teeth K^1 into 105 engagement with the extremity J^6 of the pawl J^2 in moving to the left in Fig. 5. Owing to the engagement of the extension J^4 of the pawl J^2 with the upper edge of the lever J , the pawl cannot swing about its 110 pivot and so the pawl and lever J are virtually solid and the latter is swung about its pivot J^1 to trip the catch H by means of the hooked extension J^6 . Thus the catch H is disengaged from the lever F and the 115 parts assume their positions as shown in Fig. 1. It will be readily seen that during movement of the carriage to the right of Fig. 5, that is to say under the action of its controlling-spring, the teeth K^1 engage 120 with the pawl J^2 to swing it about its pivot J^3 , and in so doing do not move the lever J .

Although a construction embodying the present invention has been described in 125 detail in connection with the accompanying drawings, the invention is not limited to the particular details described and illus-

trated provided that the spirit of the invention as defined in the appended claiming-clauses is not departed from.

What we claim as our invention and desire to secure by Letters Patent is:—

1. In a tabulating mechanism for a type-writing machine, the combination with a spring-controlled support having one or more tabulator-stops for the carriage, which support is movable in an endwise direction under its spring-control parallel with that of the carriage and also in a direction transverse thereto, and a tabulator key-lever operatively connected with said support and arranged to move to and fro in the said transverse direction, of a catch arranged to directly engage and hold the said key-lever in the position into which it is moved in releasing the carriage escapement, and tripping means arranged to operatively connect the said support with the catch and to trip the catch during the endwise movement of the support at the end of the movement of the carriage in a direction toward a tabulator stop.

2. In a tabulating mechanism for a type-writing machine, the combination with a spring-controlled support having one or more tabulator-stops for the carriage which support is movable in an endwise direction under its spring-control parallel with that of the carriage and also in a direction transverse thereto, and a tabulator key-lever operatively connected with said support and arranged to move to and fro in the said transverse direction, of a catch arranged to directly engage and hold the said key-lever in the position into which it is moved in releasing the carriage escapement, and a tripping member carried by said support and arranged to trip the catch during the endwise movement of the support at the end of the movement of the carriage in a direction toward a tabulator stop.

3. In a tabulating mechanism for a type-writing machine, the combination of a support having a tabulator-stop for the carriage, which support is movable in an endwise direction parallel with that of the carriage and also in a direction transverse thereto, a tabulator-key operatively connected with the said support and arranged to move it to and fro in the said transverse direction, a catch arranged to hold the key in the position into which it has been moved in releasing the carriage-escapement, tripping means arranged to operatively connect the said support with the catch and to trip the catch during the endwise movement of the support at the end of the movement of the carriage in a direction toward the tabulator-stop, and tripping means arranged to operatively connect the carriage with the catch to trip the latter when the carriage

is moved in a direction away from the tabulator stop.

4. In a tabulating mechanism for a type-writing machine, the combination with a tabulator key-lever of a catch to hold the key-lever in the position into which it has been moved in releasing the carriage-escapement, a trip for the catch, the said trip including a member capable of limited movement, a tabulator stop borne on said member, and means operatively connecting the said trip with a member which lies in the path of the carriage in its movement away from the tabulator-stop.

5. In a tabulating mechanism for a type-writing machine, the combination with a tabulator key-lever of a catch to hold the key-lever in the position into which it has been moved in releasing the carriage-escapement, a trip for the catch, means operatively connecting the said trip with a member which lies in the path of the carriage at the end of its movement toward a tabulator stop, and a pawl and ratchet mechanism one element of which is operatively connected with the carriage so that movement of the latter moves the said element and the other element is operatively connected with the said catch, the two elements combining to engage and trip the catch when the carriage is moved in a direction away from the tabulator-stop.

6. In a tabulating mechanism for a type-writing machine, the combination with a tabulator key-lever, of a catch to hold the key-lever in the position into which it has been moved in releasing the carriage-escapement, a trip for the catch, the said trip including a member capable of limited movement, a tabulator stop borne on said trip-member, and a pawl and ratchet mechanism, one element of which is operatively connected with the carriage so that movement of the latter moves the said element, and the other element is operatively connected with the said catch, the two elements combining to engage and trip the catch when the carriage is moved in a direction away from the tabulator-stop.

7. In a tabulating mechanism for a type-writing machine, the combination with the tabulator key-lever of a catch to hold the key-lever in the position into which it has been moved in releasing the carriage-escapement, a trip for the catch, means operatively connecting the said trip with a member which lies in the path of the carriage at the end of its movement toward a tabulator stop, a second pivoted lever, means operatively connecting the latter with the catch, a pawl and ratchet mechanism, one element of which is operatively connected with the carriage so that movement of the latter moves the said element, and the other element is borne on said second pivoted lever,

the pawl and ratchet combining to engage when the carriage is moved in a direction away from the tabulator-stop thereby moving the second pivoted lever to trip the 5 catch.

8. In a tabulating mechanism for a type-writing machine, the combination with a tabulator key-lever of a catch to hold the key-lever in the position into which it has 10 been moved in releasing the carriage-escape-
ment, a trip for the catch, the said trip including a member capable of limited movement, a tabulator stop borne on the said trip-member, a second pivoted lever, means operatively connecting the latter with the catch, a pawl and ratchet mechanism, one element of which is operatively connected with the carriage so that movement of the latter moves the said element, and the other 15 element is borne on said second pivoted lever, the pawl and ratchet combining to engage when the carriage is moved in a direction away from the tabulator-stop, thereby to move the second pivoted lever to trip the 20 catch.

9. In a tabulating mechanism for a type-writing machine, the combination with a tabulator key-lever of a catch to hold the key-lever in the position into which it has 25 been moved in releasing the carriage-escape-
ment, a trip for the catch and means operatively connecting the said trip with a member which lies in the path of the carriage at the end of its movement toward a tabulator-
stop, and other means for connecting the 30 said trip with a member which lies in the path of the carriage in its movement away from the tabulator stop, substantially as described.

40 10. In a tabulating mechanism for a type-writing machine, the combination with a tabulator key-lever of a catch to hold the key-lever in the position into which it has been moved in releasing the carriage-escape-
ment, a rail mounted for endwise movement 45 in the direction of the carriage-movement and mounted also for movement in a direction transverse to that endwise movement, a tabulator stop borne on said rail, means operatively connecting the tabulator key-lever and the rail to bring about said transverse movement when the tabulator key-lever is operated, means operatively connecting the said rail with the catch, whereby endwise 50 movement of the rail operates to trip the catch, and means operatively connecting the said trip with a member which lies in the path of the carriage in its movement away from the tabulator stop.

55 60 11. In a tabulating mechanism for a type-writing machine, the combination with a tabulator key-lever, of a catch to hold the key-lever in the position into which it has been moved in releasing the carriage-escape-

ment, a rail mounted for endwise movement 65 in the direction of the carriage movement and mounted also for movement in a direction transverse to that endwise movement, a tabulator stop borne on said rail, means operatively connecting the tabulator key-lever 70 and the rail to bring about said transverse movement when the tabulator key-lever is operated, and means operatively connecting the said rail with the catch, whereby endwise movement of the rail operates to trip the 75 catch, and a pawl and ratchet mechanism, one element of which is operatively connected with the carriage so that movement of the latter moves the said element, and the other element is operatively connected 80 with the catch aforesaid, the two elements combining to engage to trip the catch when the carriage is moved in a direction away from the stop.

12. In a tabulating mechanism for a type-writing machine, the combination with a tabulator key-lever of a catch to hold the key-lever in the position into which it has been moved in releasing the carriage-escape-
ment, a rail mounted for endwise movement 90 in the direction of the carriage movement and mounted also for movement in a direction transverse to that endwise movement, a tabulator stop borne on said rail, means operatively connecting the tabulator key-lever 95 and the rail to bring about said transverse movement when the tabulator key-lever is operated, means operatively connecting the said rail with the catch, whereby endwise movement of the rail operates to trip the 100 catch, a second pivoted lever, means operatively connecting the latter with the catch, a pawl and ratchet mechanism one element of which is operatively connected with the carriage so that movement of the 105 latter moves the said element and the other element is borne on said second pivoted lever, the pawl and ratchet combining to engage when the carriage is moved in a direction away from the tabulator stop, thereby 110 to move the second pivoted lever to trip the catch.

13. In a tabulating mechanism for a type-writing machine, the combination of a support comprising a spring-controlled rocking 115 shaft having an operating arm, which shaft is disposed parallel to the direction of movement of the carriage and is mounted so as to be capable of axial movements, and a tabulator bar fixedly mounted on said support, one or more tabulator stops on the tabulator bar, a tabulator key-lever operatively connected directly with said arm and arranged to rock the said support about the longitudinal axis of said shaft, a catch arranged to directly engage and hold the key-lever in the position into which it is brought in rocking said support and releasing the 120 125

carriage escapement, and a tripping member fast on said support and arranged to trip the catch during the endwise movement of said support at the end of the movement of the carriage in a direction toward a tabulator-stop.

In testimony whereof we have signed our
